UNITED STATES PATENT OFFICE.

MARIO PERUZZI, OF WILKES-BARRE, PENNSYLVANIA, ASSIGNOR TO PLANTERS NUT & CHOCOLATE COMPANY, OF WILKES-BARRE, PENNSYLVANIA, A CORPORATION OF PENNSYLVANIA.

DESIGN FOR A PEANUT BOOTH.

Application filed November 30, 1928. Serial No. 29,068. Term of patent 14 years.

To all whom it may concern:

Be it known that MARIO PERUZZI, citizen of the United States, residing at Wilkes-Barre, in the county of Luzerne and State of Pennsylvania, has invented a new, original, and ornamental Design for Peanut Booth, as shown in the accompanying drawing and described in the following specification.

The figure in the drawing shows a perspective view of a peanut booth illustrating my new design.

I claim:

The ornamental design for a peanut booth as shown.

MARIO PERUZZI.
